UNITED STATES PATENT OFFICE.

HERBERT A. SMITH, OF PICKFORD, MICHIGAN.

DRYING-RACK FOR NEGATIVES.

1,165,724.

Specification of Letters Patent. Patented Dec. 28, 1915.

Application filed November 16, 1914. Serial No. 872,451.

To all whom it may concern:

Be it known that I, HERBERT A. SMITH, a citizen of the United States, residing at Pickford, in the county of Chippewa, State of Michigan, have invented certain new and useful Improvements in Drying-Racks for Negatives; and I do hereby declare the following to be a full, clear, and exact description of the invention, such as will enable others skilled in the art to which it appertains to make and use the same.

This invention relates to improvements in drying racks and particularly to racks for drying photographic negatives.

One object of the invention is to provide a drying rack of this character which can be secured to the edge of a table or bench.

Another object is to provide a negative drying rack which can be so adjusted as to securely hold a plurality of negatives of different sizes at the same time.

Other objects and advantages will be apparent from the following description when taken in connection with the accompanying drawings.

In the drawings: Figure 1 is a front elevation of a negative drying rack made in accordance with my invention, Fig. 2 is an end view of the same, Fig. 3 is a top plan view and Fig. 4 is a transverse sectional view on the line 4-4 of Fig. 3.

Referring particularly to the accompanying drawing 10 and 11 represent legs pivotally connected in pairs. The upper ends 35 of the members 10 are longer than the corresponding ends of the members 11 and extending between these longer ends and connected in parallel relation on the said members are the strips 12 and 13. These 40 strips are formed with the notches 14 for reception of one edge of the negatives 15, the lower strip 13 being slightly longer than the other strip and projecting a slight distance beyond each of the members 10. Connecting the upper ends of the members 11 is a strip 16 also provided with notches 17. A member 18 which has a plurality of notches or recesses 19 formed in one longitudinal face is secured to the rear of the 50 strip 16 by means of the bolts 20 with the

notches directed toward the said strip. Disposed in each of the notches is a pin 21, the upper end of which is formed with an angularly extending portion 22, the lower face of which has a longitudinal groove 23. 55 It will be noted that the recesses are so arranged with respect to the notches 17 of the strip 16 that one of the pins 21 is disposed behind each of the said notches, the angular projecting portions 22 being thus 60 in position to engage the upper edges of the negatives. Disposed through the recesses, behind the pins are the wedge strips 24, the lower or smaller ends of each of which have laterally projecting portions 25 65 which prevent removal of the wedge from the recesses until after the pins are removed. By means of these wedges, the pins can be firmly held in different positions in the recesses. Thus negatives of different sizes can 70 be clamped in the rack by adjusting certain of the pins so that the angular projecting portion will engage one edge thereof.

Pivots connected to the lower end of each of the members 10 is a suitable clamp 75 26, these clamps being adapted for clamping engagement with the edge of a table or bench to firmly hold the rack against being knocked over. The pins and their projections firmly clamp the negatives in the rack 80 so that the same can not be jarred out of place should any object come in contact with the rack. By swinging the clamps on their pivots they can be moved to rest against the projecting portions of the strip 13 so that 85 the clamps will be out of the way when the rack is to be carried or set on a table.

From the foregoing it will readily be seen that I have provided a novel and efficient device for supporting photographic 90 negatives and one in which the negatives are prevented from being jarred out of place and also one in which the rack itself is held from movement.

What is claimed is:

A negative drying rack comprising a frame including crossed pivoted end supporting members, means carried by certain of the supporting members for detachably securing the same to a support, notched neg- 100

ative receiving strips connecting the supporting members, a recessed member carried by one of the strips, the recesses of which are disposed at the rear of the notches of the said strip, pins slidably disposed through the notches, plate engaging elements carried by the pins, and wedge members disposed in the recesses and arranged to

hold the pins at different points of adjustment through the recesses.

In testimony whereof, I affix my signature, in the presence of two witnesses.

HERBERT A. SMITH.
